PATTERN CONTROL FOR SHUTTLE CHANGING MECHANISM

Richard G. Turner, Worcester, Mass., assignor to
Crompton & Knowles Loom Works, Worcester,
Mass., a corporation of Massachusetts

Application September 11, 1936, Serial No. 100,349

12 Claims. (Cl. 139—232)

This invention relates to improvements in looms and it is the general object of the invention to provide a loom operating with a number of weaving shuttles certain of which may be changed automatically when exhausted and others of which may act to stop the loom for hand replenishment.

In the weaving of certain patterns one or two colors predominate while others are used only occasionally for decorative effects. For efficient weaving the frequently used wefts should be renewed automatically, but those yarns which are used for decoration only can advantageously be replenished by hand.

15 In my co-pending application Serial No. 9,645 I have set forth a loom for accomplishing this general result, a single weft detector being employed in connection with a control exercised by the pattern to effect automatic changing of two 20 shuttles and loom stoppage with respect to two other shuttles. My present invention relates more particularly to the control for the selector mechanism of the shuttle changer and it is accordingly a further object of my invention to provide 25 improved means for moving the selector to one of two positions in either of which the selector is operative to control the shuttle changing magazine, while the third position moves the selector out of operative position to prevent shuttle 30 changing operation when exhaustion occurs in one of the infrequently used shuttles.

When looms of the type to which my invention relates are operated at high speed it is desirable that the selector be given its complete setting with respect to the shuttle changing mechanism 35 as early as possible in the cycle of loom operation, and it is another object of my invention to provide means wherein the selector can be placed very shortly after the shuttle boxes start their shifting motion. In this way the magazine for the shuttle changer can begin its operations without waiting for the complete shifting movement of the drop boxes.

40 For positive and efficient operation at high speed it is desirable to use the so-called Knowles head for shifting the harnesses and drop boxes and it is another object of my invention to adapt the Knowles head to a loom of the type specified so that the movement of the selector may be completed during approximately the first third 45 of the shuttle box shift caused by the Knowles head mechanism.

With these and other objects in view which will appear as the description proceeds, my invention resides in the combination and arrange-

ment of parts hereinafter described and set forth.

In the accompanying drawings, wherein a convenient embodiment of my invention is set forth,

Fig. 1 is a front elevation of a loom having my invention applied thereto,

Fig. 2 is an end elevation taken in the direction of arrow 2, Fig. 1, the shuttle box being shown in section,

Fig. 3 is a detailed end elevation taken in the direction of arrow 3, Fig. 1,

Fig. 4 is a rear elevation on an enlarged scale of the Knowles head and connection therefor shown at the upper left part of Fig. 1,

Fig. 5 is a diagrammatic view showing the relation between the two cams operated by the head motion, together with the fingers controlled thereby,

Figs. 6 and 7 are diagrammatic views on a reduced scale showing the structure of Fig. 4 in different positions,

Fig. 8 is an end elevation looking in the direction of arrow 8, Fig. 4,

Fig. 9 is a plan on an enlarged scale taken in the direction of arrow 9, Fig. 3, and

Fig. 10 is a vertical section on line 10—10, Fig. 3, on an enlarged scale.

Referring to Figs. 1 and 2, I have shown a loom frame 15 having a lay 16 provided with a gang 17 of shifting shuttle boxes having cells 18, 19, 20 and 21, the latter being the lowest cell. The 30 boxes are supported by a box lifter rod 22 which is given various vertical settings by means of a flexible connector 23 the upper part of which extends around a fixed sheave 24 and a movable sheave 25 and is fastened to a lever 26 mounted 35 on the loom frame. The movable sheave 25 is mounted on the lower end of a lever 27 pivoted as at 28 and movable about the latter as a fixed axis.

The Knowles head K has upper and lower 40 constantly running milled cylinder gears 30 and 31, respectively, which are driven in opposite directions by well-known connections not shown. For the purposes of the present invention I illustrate in detail two vibrator levers 32 and 33, 45 respectively, pivoting about a heel pin 34 and carrying vibrator gears 35 and 36, respectively. Gear 35 is provided with a connector 37 pivotally connected as at 38 to the upper end of lever 26, whereas gear 36 has a longer connector 39 pivotally connected as at 40 to lever 27.

A pattern chain 41 having high and low rolls 42 and 43, respectively, positions the vibrator levers 32 and 33 according to the requirements of the pattern being woven. The cylinders 30 55

and 31 operate the vibrator gears to transmit an operating force to the levers 26 and 27, each of the latter being capable of taking two positions so that there are four possible combinations of 5 positions for said levers 26 and 27.

As shown in Fig. 4 the levers 26 and 27 are in their left hand position and the chain 23 is therefore in its lowest position corresponding to the location of upper cell 18 in picking or active 10 position with respect to the lay. When cell 19 is to be active, lever 26 will be moved to the right to the dotted line position of Fig. 6, the sheave 25 remaining stationary. When cell 20 is to be active lever 26 remains to the left, and lever 27 15 will be rocked in a right hand direction to the position of Fig. 7. Should it be desired to place cell 21 for picking both levers will be rocked to the right, as shown in Fig. 7.

It will be seen therefore that the placing of 20 upper cells 18 and 19 for picking involves only the shifting of lever 26 from one to the other of its positions while lever 27 remains at rest in the position of Fig. 4. Further, it will be seen that when either of the lower cells 20 or 21 is to be 25 active lever 27 will be to the right, as shown in Fig. 7, whatever the position of lever 26. These facts as to the relation between the positions of levers 26 and 27 relatively to the upper and lower pairs of cells shown in Fig. 2 is made use of as 30 set forth hereinafter to control the selector for the shuttle changer to be described hereinafter.

The shuttle changer mechanism C shown in Fig. 1 includes a magazine M to provide two different types of reserve shuttles and the lay at 35 that end of the loom has upper and lower shuttle changing boxes 50 and 51, respectively, which are normally down but which are elevated by rod 52 whenever a shuttle changing operation is to occur. A control lever 53 reciprocates a rod 40 54 the left end of which is viewed in Fig. 3 is connected to a slide 55 mounted on guide rods 56. The latter are carried by a lever 57 and permit the slide 55 to assume three different positions shown in full, dotted and dot-and-dash positions 45 in Fig. 9.

The slide carries a pin 58 on which are pivotally mounted two selector elements 59 and 60, respectively, each capable of being set by a trip 51 to be elevated by a solenoid 62 controlled by 50 an electric feeler mechanism not shown. The elements 59 and 60 control a lifter dog 63 shown in Fig. 10, either of the elements when set in the changing position of element 59 being capable of directing the dog into lifting relationship with 55 respect to lever 57 for the purpose of lifting the rod 52. An actuator lever 68 is oscillated regularly about an axis 48 by cam 69 on alternate loom beats to elevate the dog member 63.

The lower end of control lever 53 is attached 60 to a connector 65 which extends across the loom to the left or head end as viewed in Fig. 1, and my present invention is related more particularly to means for moving this connector 65 so that the lever 53 and therefore the slide 55 can be given one or the other of three positions.

When the slide 55 is either in the full or the dotted line position shown in Fig. 9 the dog 63 65 will be under the control of one or the other of the selector elements 59 or 60, but when the slide 70 65 assumes the dot-and-dash position shown in Fig. 9 the elements 59 and 60 will move out of registering position with respect to the dog 63 so that under this last named condition a shuttle changing operation cannot occur.

Lever 53 also controls the position of maga-

zine actuating hooks 64 and 66 with respect to a pin 67 on lever 57, hook 66 being in the path of the pin when cell 18 is active and hook 64 being operative with respect to the pin when cell 19 is active. For further details reference may be had to my copending application Serial No. 9,645 filed March 6, 1935.

The matter thus far described may be as heretofore proposed, the shifting boxes for Knowles head at the left hand end of the loom as shown 10 in Fig. 1 being of the common construction, while the shuttle changer mechanism illustrated at the right hand side of Fig. 1 may be the same as that set forth in copending applications Serial Nos. 460,746, 667,464; 747,358 and 560,573. It is sufficient for the purpose of the present description to state that a loom operating with the four shuttles S', S², S³ and S⁴ as shown in Fig. 2 can be controlled so that any one of these shuttles can become active and remain active as long as 20 desired, but that under the present assumption the upper cells 18 and 19 will be quite active, whereas the lower cells 20 and 21 will be relatively inactive, and it may further be stated that the two types of reserve shuttles supplied by the 25 changer C correspond to the weft carried in the shuttles S' and S² corresponding to the upper pair of cells at the drop box end of the loom. It may also be stated that a shuttle changing operation will be called for whenever the lever 53 is 30 in the full or dotted position shown in Fig. 3 corresponding to the full or dotted position of the slide 55 in Fig. 9, and that whenever lever 53 is in the dot-and-dash line position of Fig. 3 to place the slide 55 in the dot and dash position 35 of Fig. 9 a shuttle changing operation will be impossible due to non-registry between the dog 63 and the elements 59 and 60.

Coming more particularly to my present invention I provide means for giving the connector 65 40 the three positions already referred to. As shown in Figs. 1 and 4, this connector is attached to a vertical rod 70 connected to a lever 71 movable about a fixed axis 72 carried by the loom frame. This lever is provided with two adjustable lifting 45 screws 73 and 74, respectively, corresponding to levers 26 and 27, respectively. A pin 75 carried by lever 71 has pivoted thereon two levers 76 and 77 for the screws 73 and 74, respectively. Each of these levers has a lifting arm 78 by which the 50 corresponding screw may be lifted to position the lever 71. Each lever is also provided with a swivel pin 79 by means of which lever 76 is connected to a cam finger 80, while lever 77 is connected to a similar cam finger 81. The fingers 80 55 and 81 are spaced as shown in Fig. 8 to cooperate with cams 82 and 83, respectively.

Cam 82 is on a lever 85 movable about the fixed axis 28 and driven by a connector 86 attached as at 87 to lever 26 see Fig. 4. When lever 26 moves 60 to the left the connector 86 will rock lever 85 in a right hand direction to lower the cam 82 to the position shown in Fig. 4. The other cam 83 is on a lever 90 bolted at 91 to lever 27 and is also movable about the fixed axis 28. When lever 27 is 65 rocked to the left as viewed in Fig. 4 the cam 83 will be raised, but when said lever 27 is rocked to the right cam 83 will be down, as shown in Fig. 7. Tension springs 84 between lever 71 and small levers 76 and 77 hold the fingers 80 and 81 against 70 their cams.

The cams 82 and 83 are especially formed as illustrated in Figs. 4, 5 and 8. Cam 82 has two parallel runs 100 and 101, run 100 having a low dwell 102 at the upper part thereof, an incline 103, 75

and a moderately high dwell 104 at the same level as a short moderately high dwell 105 on run 101. Above dwell 105 is a decline 106 terminating at a relatively long low dwell 107 which is at the level of dwell 102. Switches 108 yieldingly positioned by a spring 109 and pivoted at 110 permit a shoe 111 of finger 80 to move along the various parts of the runs 100 and 101 in a clockwise direction as viewed in Fig. 8. With cam 82 in the position shown in Fig. 8 the shoe 111 is in the short low dwell 102 and soon after lever 26 starts to move to effect a shifting of the boxes 18 and 19, said shoe will ride up the incline 103, thereby rocking lever 16 to cause an elevation of screw 73 and lever 71 early in the shifting of the boxes, preferably no later than the first one-third of the interval of time required for the box shift. As the shift nears completion the shoe will be cammed by surface 112 to the left, swinging the lower switch 108 so that the shoe 111 passes into the run 101 where it will remain until there is to be another shift of boxes 18 or 19 effected by levers 26. When this second shift occurs the cam 82 will move down from the raised dotted line position of Fig. 6, causing motion of the shoe 111 along the short moderately high dwell 105, down the decline 106 and on to the low dwell 107, effecting a lowering of the lever 71 early in the box shift. As lever 26 nears the end of this second shift the upper switch 108 will yield as the shoe moves along cam surface 113.

The difference in elevation between the dwells 102 and 107 at the upper end of cam 82 and dwells 104 and 105 at the lower end effects a small shift 35 of lever 71 corresponding to a movement of boxes 18 or 19 toward or from active position. During such a shift of cam 82 by lever 26 it will be possible to effect automatic shuttle changing operations of the loom relatively to either shuttle S' or S² by 40 controls already described.

The other cam 83 is similar to cam 82 and has runs 120 and 121, respectively, along which a shoe 122 of finger 81 slides. The switches and spring control for cam 83 are similar to those of cam 82. 45 Run 120 has a short low dwell 125, an incline 126, and a relatively high long dwell 127, while run 121 has an upper short high dwell 128, a decline 129, and a long low dwell 130. Dwells 125 and 130 are at the same level, and dwells 127 and 128 50 are at the same level. The shoe 122 moves in a counter-clockwise direction with respect to the runs 120 and 121 as the cam 83 reciprocates, the switches yielding as already described in connection with cam 82. As with the latter, the incline 126 and decline 129 come into action shortly after 55 the cam 83 starts to shift.

In cam 83 the difference in level between the high and low dwells is considerably more than is the case with cam 82, therefore the lever 71 will be 60 given a relatively greater angular motion about 75 when cam 83 moves, and this greater motion gives lever 71 a large shift. Due to this larger motion of lever 71, the control lever 53 has a maximum throw, moving slide 55 so that a shuttle changing operation will be impossible.

It is believed that the operation of the invention will be understood from the foregoing description. When boxes 18 or 19 are active cam 83 will be at 70 rest and in the raised position shown in Fig. 4, while the cam 82 will be rocked either to its high or low position, depending upon the location of lever 26. The oscillation of cam 82 will give lever 71 a relatively small shift so that slide 55 will be 75 either in the full or the dotted line position shown

in Fig. 9, permitting shuttle changing operations. Whenever boxes 20 or 21 are active, however, lever 27 will be in the position shown in Fig. 7 causing cam 83 to be down to place a high dwell 127 or 128 under shoe 122 to give lever 71 a relatively large 5 motion which will move slide 55 to the dot and dash position shown in Fig. 9, rendering a shuttle changing operation impossible.

The trip 61 has a narrow foot 95 which registers with element 59 or 60 whenever cell 18 or 19 is 10 active, but when either cell 20 or 21 is active the elements move to a position out of alignment with the foot as in the dotted, and dot-and-dash positions of Fig. 8. Under these conditions the foot can rock with the trip without causing the latter 15 to set either element.

From the foregoing it will be seen that I have provided means whereby a shuttle changing mechanism may be either operative or inoperative depending upon which of the shuttleboxes 20 18, 19, 20 or 21 is active. It will be seen that this control is effected by means of two cams movable by the vibrator gears of the well-known Knowles head, each cam having high and low dwells for each of two runs so that the shoes corresponding thereto can be given an operative motion early in the shift of the shuttle boxes whether the latter be rising or falling. In actual practice the third position of the selector, that is, the position in which the latter cannot operate the magazine, is used in association with mechanism to stop the loom, but this latter feature does not form part of the present invention.

Having thus described my invention it will be seen that changes and modifications may be 35 made therein by those skilled in the art without departing from the spirit and scope of the invention and I do not wish to be limited to the details herein disclosed, but what I claim is:

1. In a weft replenishing loom, a pair of shifting shuttle boxes, weft replenishing mechanism to supply two distinctive types of reserve weft, a selector for the weft replenishing mechanism to determine which type of reserve weft is to be selected, means to shift the shuttle boxes so 45 that either box is rendered active, a cam operated by said means and having two tracks, each track having high and low areas, cam follower means in engagement with the cam and connected to the selector to move the latter, mechanism to transfer the cam follower means from one track to the other when the direction of motion of the cam is reversed, the length of the areas of the two tracks being unequal when measured from any given point of reversal. 55

2. In a weft replenishing loom, a pair of shifting shuttle boxes, weft replenishing mechanism to supply two distinctive types of reserve weft, a selector for the weft replenishing mechanism to determine which type of reserve weft is to be 60 selected, means to shift the shuttle boxes so that either box is rendered active, a cam movable in timed relation with the box shifting means and having two tracks, a lever connected to the selector to be successively operated by the tracks, 65 and means to shift the lever from one track to the other track when the direction of motion of the cam is reversed, each track having high and low areas, the high and low areas of either track being of unequal length. 70

3. In a weft replenishing loom, a pair of shifting shuttle boxes having two cells either of which is movable to active position, weft replenishing mechanism to supply two distinct types of reserve weft, a selector to determine 75

- which type of reserve weft is to be supplied by the replenishing mechanism, means to shift the shuttle boxes, a pair of cam tracks each of which has an incline, a lever to be shifted by the incline of either track and connected to the selector, and means to cause the lever to shift from one track to the other track when the first named means shifts the shuttle boxes, the inclines of the tracks being at different distances from the point at which said lever is shifted with respect to the tracks.
4. In a weft replenishing loom, a pair of shifting shuttle boxes having two cells either of which is movable to active position, weft replenishing mechanism to supply two distinct types of reserve weft, a selector to determine which type of reserve weft is to be supplied by the replenishing mechanism, means to shift the shuttle boxes, a pair of cam surfaces each having an incline movable by the means which shifts the shuttle boxes, a lever to be rocked by the incline of each cam surface and connected to the selector, means to shift the lever from one cam surface to the other cam surface when the boxes are shifting, and means to prevent the lever from returning to said one cam surface from the other cam surface after the shift, the inclines being at different distances from the point at which the lever shifts from one cam surface to the other.
5. In a weft replenishing loom, a pair of shifting shuttle boxes having two cells either of which is movable to active position, weft replenishing mechanism to supply two distinct types of reserve weft, a selector to determine which type of reserve weft is to be supplied by the replenishing mechanism, means to shift the shuttle boxes, a pair of similar cam surfaces movable together and operated by said means when the boxes are shifting, a lever to be operated by the cam surfaces, means to cause the lever to shift from one cam surface to the other cam surface when there is to be a shift of the boxes, and means to cause the lever to move from one cam surface to the other cam always in the same direction.
6. In a weft replenishing loom, a pair of shifting shuttle boxes having two cells either of which is movable to active position, weft replenishing mechanism to supply two distinct types of reserve weft, a selector to determine which type of reserve weft is to be supplied by the replenishing mechanism, means to shift the shuttle boxes, two cams rigid with respect to each other and movable together by the means which shift the shuttle boxes, an incline for each cam, the incline of one cam being nearer one end of said cam than the other end and the incline of the other cam being farther from said one end than the first incline, a lever connected to the selector to be operated successively by the inclines, and means to cause said lever to be operated first by one incline and then by the other incline as said cams are reciprocated.
7. In a weft replenishing loom, a pair of shifting shuttle boxes having two cells either of which is movable to active position, weft replenishing mechanism to supply two distinct types of reserve weft, a selector to determine which type of reserve weft is to be supplied by the replenishing mechanism, means to shift the shuttle boxes, a cam having an end and two connecting tracks, each track having an incline, means to move the cam in timed relation with the shuttle boxes, a lever connected to the selector to engage the

tracks, and means to cause the lever to engage the tracks successively as the cam reciprocates, the inclines being at unequal distances from said end of the cam.

8. In a multicolor shuttle changing loom, shuttle changing mechanism, a member to be moved to assist in an operation of the shuttle changing mechanism, an actuator for the member normally idle with respect to the latter, two controllers for the actuator each capable of connecting the actuator with the member, support means for the controllers movable to give the latter three different positions one position of which is out of register with said actuator, a set of shifting shuttle boxes having three or more cells, two vibrators and vibrator gears for the boxes, a cam for and movable by each vibrator gear, connections between the vibrator gears and the shuttle boxes to move the latter when the gears move connecting means between one of the cams and the controllers effective when either of two shuttle boxes is active to place the controllers for operation with the actuator, and connections between the other cam and the controllers effective when other than said two shuttle boxes are active to move the controllers to said third position out of registry with respect to the actuator.

9. In a multicolor shuttle changing loom, shuttle changing mechanism, a member to be moved to assist in an operation of the shuttle changing mechanism, an actuator for the member normally idle with respect to the latter, two controllers for the actuator each capable of connecting the actuator with the member, support means for the controllers movable to give said controllers three different positions one position of which is out of registry with said actuator, a set of shifting shuttle boxes having three or more cells, two vibrators and vibrator gears to move the boxes, a cam having a relatively low incline to be connected to and moved by one of the vibrators, a second cam having a relatively high incline connected to and operated by the other vibrator gear, connections between one of the vibrator gears and the boxes to render either of two cells active, connections between the other vibrator gear and the boxes to assist in rendering cells other than said two active, moving means for the controllers, connections between the first cam and said moving means to cause the latter to move with the actuator when either of said two cells is active, and connections between the second cam and said moving means to cause the latter to move said controllers to the third position out of registry with the actuator when some other than said two cells is active.

10. In a multicolor shuttle changing loom, shuttle changing mechanism, a member to be moved to assist in an operation of the shuttle changing mechanism, an actuator for the member normally idle with respect to the latter, two controllers for the actuator each capable of connecting the actuator with the member, support means for the controllers movable to give said controllers three different positions one position of which is out of register with said actuator, a set of shifting shuttle boxes having three or more cells, two vibrators and vibrator gears, a reciprocable cam having two tracks each with a relatively low incline, means to connect one of said vibrator gears to said cam to move the latter, a second reciprocable cam having two tracks each with a relatively high incline, means to connect the other vibrator gear to the other cam

to move same, moving means for the controllers, said cams to be reciprocated by their respective vibrator gears, connections between the first cam and the controllers to give the latter either of 5 two positions in register with the actuator by movement of said first cam in either direction, and connections between the other cam and the controller to give the latter said third position out of register with the actuator by a movement 10 of the second cam in either direction.

11. In a multicolor shuttle changing loom, shuttle changing mechanism, a member to be moved to assist in an operation of the shuttle changing mechanism, an actuator for the member normally idle with respect to the latter, two controllers for the actuator each capable of connecting the actuator with the member, support means for the controllers movable to give said controllers three different positions one position 20 of which is out of register with said actuator, a set of shifting shuttle boxes having three or more cells, two vibrators and vibrator gears, a cam reciprocable having two tracks each with a relatively low incline connected to one of the 25 vibrators, a second reciprocable cam having two tracks each with a relatively high incline connected to the other vibrator gear, moving means for the controller, connecting means to cause each vibrator gear to reciprocate the corresponding cam, connections between the first cam and the controllers to give the latter either of two

positions in register with the actuator by movement of said first cam in either direction, and connections between the other cam and the controller to give the latter said third position out of register with the actuator by a movement of 5 the second cam in either direction, the inclines of the cams being placed to effect movement of the connections to the controllers when said cams have moved approximately one-third of their whole motion from one position to the other. 10

12. In a multi-color loom, weft replenishing mechanism to supply two distinctive types of reserve weft, shifting shuttle boxes having more than two cells any one of which may become active, a selector for the replenishing mechanism 15 to have two operative positions with respect to said replenishing mechanism, a pair of levers each movable to two positions, means connecting the levers to the shuttle boxes to impart motion to the latter derived from the levers, a pair of 20 cams connected to and movable together by one of said levers, connecting means to connect the selector with either cam one at a time, and control mechanism for the connecting means to cause one only of the pair of cams to move the connecting means when the cams move in one direction, and said control mechanism to cause the other 25 cam only of the pair of cams to move the connecting means when the cams move in the opposite direction. 30

RICHARD G. TURNER.
